TOOL FOR REMOVING DENTS IN MUSICAL INSTRUMENT TUBES

Robert E. Weber, Rte. 2, Box 2979, Loomis, Calif., assignor of one-half to Lester E. Lehr, Sacramento, Calif.

Filed Feb. 11, 1963, Ser. No. 73,560

Term of patent 14 years

(Cl. D54—13)

FIG. 1 is an upper front perspective view of a tool for removing dents in musical instrument tubes, showing my new design;

FIG. 2 is a lower rear perspective view;

FIG. 3 is a side elevational view; and,

FIG. 4 is a front elevational view.

I claim:

The ornamental design for a tool for removing dents in musical instrument tubes, as shown.
